(57) CLAIM

The ornamental design for a pot holder, as shown and described.

DESCRIPTION

FIG. 1 is a perspective view of a pot holder;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an exploded perspective view thereof; and,

FIG. 9 is a perspective view thereof, shown in an environment of use.

The dash-dot-dash broken lines shown in FIG. 8 indicate how the separated pieces of the design assemble and form no part of the claimed design. The evenly-spaced broken lines shown in FIG. 9 depict environmental subject matter only and form no part of the claimed design.
